UNITED STATES PATENT OFFICE.

CLARENCE B. BOWLING, OF DETROIT, MICHIGAN.

DENTAL FLOSS-HOLDER.

1,158,890.

Specification of Letters Patent.

Patented Nov. 2, 1915.

Application filed March 6, 1915. Serial No. 12,668.

To all whom it may concern:

Be it known that I, CLARENCE B. BOWLING, a citizen of the United States, residing at Detroit, in the county of Wayne and State of Michigan, have invented a new and useful Dental Floss-Holder, of which the following is a specification.

The present invention appertains to a dental floss holder, and aims to provide a novel and improved device of that character.

The object of the invention is the provision of a dental floss holder having novel and efficient means for holding the floss, and whereby the active portion of the floss may be readily renewed and tightened.

It is also within the scope of the invention to provide a dental floss holder of comparatively simple and inexpensive construction, and which may be readily carried in the pocket, purse, or the like, which will be convenient, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a side elevation of the improved dental floss holder. Fig. 2 is a longitudinal section thereof. Fig. 3 is a cross sectional view taken on the line 3—3 of Fig. 1. Fig. 4 is a cross section on the line 4—4 of Fig. 2.

In carrying out the invention, there is provided a tubular handle 1 preferably constructed of metal, and having one end open while the other end is preferably rounded.

A cap or plug 2 is threaded into the open end or mouth of the handle 1, whereby the handle is adapted to hold the cop or cartridge of floss. The cap 2 of the handle carries a bow 3, which comprises a rod 4 having one end portion threaded through the cap or plug 2, and having its outer or free end portion extending angularly, as at 5. The bow 3 carries an arm 6 having an eye or bearing 7 slideable upon the rod 4 adjacent the cap or plug 2, and the arm 6 projects in the same direction as does the end portion

or arm 5 of the rod 3. The arm 6 is prevented from rotation about the rod 3, by means of a feather 8 carried by the eye or bearing 7 and engaging a longitudinal featherway 9 provided in the rod 4. In this manner, the arm 6 is adjustable longitudinally upon the rod 4, and will be maintained in the same plane as the bow 3 and its arm 5. As a means for adjusting the arm 5 upon the rod 4, a nut 10 is threaded upon the rod and bears against the bearing 7 to move the bearing toward the cap 2 when the nut is screwed inwardly. The free or lower ends of the arms 5 and 6 are provided with the rounded slotted heads 11 and 12, respectively, and the arm 5 and adjacent portion of the body of the rod 4 is covered by rubber tubing or similar covering 13, while the arm 6 is covered by rubber tubing or other covering 14, so that the covered portions will be protected, and thereby render the device sanitary. A set screw 15 is threaded into the projecting portion of the cap 2 and bears against the rod 4 for holding the rod in place with respect to the cap, and the cap 2 is provided with an aperture 16 at one side of its center and arranged at one side of the set screw 15. The handle 1 is adapted to receive the cop, cartridge or spool of floss 17, and the strand 18 of floss is adapted to pass outwardly through the aperture 16, thence around the set screw 15 between the head thereof and cap 2, thence to the slotted head 12 of the arm 6, and thence through the slotted head 11 of the arm 5.

If the floss is carried by a spool, the spool may be conveniently held for rotation within the handle 1, by means of a member 19 threaded upon the inner end of the rod 14 and having an inwardly projecting spindle 20 for holding the spool, whereby the spool may rotate readily as the floss is unwound therefrom and drawn out through the aperture 16. It will be understood, however, that the member 19 may be detached and removed for allowing the cop or cartridge of floss to be disposed loosely within the handle when so desired.

In use, by removing the cap 2 from the handle 1, this being preferably accomplished by unscrewing the handle from the cap, the cop or cartridge 17 of floss may be readily inserted in the handle, and the strand of floss may then be passed outwardly through the aperture 16. Then, the handle 1 and cap 2 are re-assembled, and the strand 18 is

passed to one side from the aperture 16 and around the shank of the set screw 15. The strand 18 is then passed through the slot of the head 12, and is then extended across the 5 bow 3 to the head 11 of the arm 5. The free portion of the strand 18 is engaged through the slot of the head 11 and is then wound around the said head 11 to secure the free end of the strand firmly to the free end of 10 the bow 3. The set screw 15 not only serves to secure the rod 4 to the cap 2, but also serves as a friction device for the strand 18, as will be apparent. When the strand 18 is applied to the bow, the nut 10 is preferably 15 loosened, so that the arm 6 can be moved away from the cap 2, and then after the strand 18 is applied to the arms 6 and 5, the nut 10 may be screwed toward the handle 1, to move the arm 6 away from the arm 5 and 20 to thereby render that portion of the strand 18 between the arms 5 and 6 taut.

What is claimed is:

1. A dental floss holder comprising a handle having floss holding means, and a bow 25 carried by the handle and embodying a rod carried by the handle and having floss engaging means at its free end, and an arm adjustable longitudinally upon the rod and having floss engaging means.
- 30 2. A dental floss holder comprising an open ended hollow handle, a cap engaged to the open end of the handle and having an aperture therein for the passage of floss therethrough, and a bow comprising a rod 35 carried by the cap and having floss engaging means at its free end, and an adjustable arm carried by the rod and having floss engaging means.
3. A dental floss holder comprising a handle 40 having floss holding means, a bow embodying a rod carried by the handle, and an arm slidable upon the rod, the arm having floss engaging means, and a nut threaded upon the rod and coöperating with said arm 45 to move the same along the rod for tightening the floss.

4. A dental floss holder comprising a handle having means for holding floss, a bow comprising a rod carried by the handle and an arm slidable upon the rod, the free end 50 of the rod and arm having floss engaging means, and a nut threaded upon the rod and coöperating with the said arm to move the same away from the free end of the rod.

5. A dental floss holder comprising a hollow handle having one end open, a cap engaged in the open end of the handle and having an aperture for the passage of floss therethrough, a rod engaged through the cap, floss engaging means carried by the 60 rod, and a spindle attachable to the inner end of the rod to project within the handle for holding floss thereon.

6. A dental floss holder comprising a hollow handle adapted to hold floss therein and 65 having one end open, a cap engaged in the open end of the handle and having an aperture therein for the passage of floss therethrough, a friction device for the floss carried by the cap, a bow carried by the cap 70 and embodying a rod carried by the cap, and an arm adjustable upon the rod adjacent the cap, the free end of the rod and said arm having floss engaging means.

7. A dental floss holder comprising a hollow floss holding handle having one end open, a cap engaged in the open end of the handle and having an aperture therein for the passage of floss therethrough, a bow comprising a rod carried by the cap and an 80 arm slidable upon the rod adjacent the cap, the free end of the rod and said arm having floss engaging means, and a nut threaded upon the rod and bearing against the said arm to move the same toward the cap.

In testimony that I claim the foregoing as my own, I have hereto affixed my signature in the presence of two witnesses.

CLARENCE B. BOWLING.
